UNITED STATES PATENT OFFICE.

FRANCIS J. PRIDEAUX, OF ADRIAN, MINNESOTA.

CHIMNEY FOR OIL-BURNING COOK-STOVES.

1,361,491.

Specification of Letters Patent.

Patented Dec. 7, 1920.

Application filed March 19, 1920. Serial No. 367,081.

To all whom it may concern:

Be it known that I, FRANCIS J. PRIDEAUX, a citizen of the United States, resident of Adrian, county of Nobles, State of Minnesota, have invented certain new and useful Improvements in Chimneys for Oil-Burning Cook-Stoves, of which the following is a specification.

In the operation of the well-known oil burning stoves for cooking purposes, using one or more burner flames, it has been discovered that in cooking or roasting meats or other articles of food there frequently is insufficient heat in the burner directly beneath the kettle in which the food may be cooking to cook it as rapidly as desired and difficulty is also experienced when a boiler is placed over two of the burners and water is being heated for clothes washing purposes.

The object of my invention, therefore, is to provide a flue connection between contiguous chimneys by means of which two burners may be coupled together and the heat delivered to the one chimney over which the kettle or other cooking utensil may be placed.

A further object is to provide an attachment which can be easily and quickly adapted for the metal chimneys in general use on stoves of this type.

Other objects of the invention will appear from the following detailed description.

The invention consists generally in various constructions and combinations, all as hereinafter described and particularly pointed out in the claims.

In the accompanying drawings forming part of this specification,

Figure 1 is a front elevation of an oil burning cook stove embodying my invention,

Fig. 2 is a detail view showing the different positions in which the damper located in the flue may be adjusted,

Fig. 3 is a sectional view on the line 3—3 of Fig. 2.

Fig. 4 is a view of the cover removed from the chimney.

In the drawing, 2 represents the base of the stove, 3 is the body portion thereof and 4 the top, having the usual openings 5 on which the cooking utensil is placed. 6 represents a suitable reservoir for the fuel oil,

7 a pipe leading therefrom and 8 one of a plurality of burners communicating with

the pipe and above which the well known metal chimney 9 is mounted, having a door 10 through which access may be had to the burner. All this mechanism is of ordinary construction and in general use in stoves of this type.

For the purpose of enabling the cook to utilize the heat of two burners in one chimney, I provide contiguous chimneys with pipe sections 11 and 12 fitted over openings formed in the chimneys and having their ends arranged to telescope, stove-pipe fashion, as indicated by the dotted line in Fig. 2. These pipe sections, when joined together, form a flue leading from one chimney to an adjoining one, and the flue is preferably upwardly inclined so that the heat from the burner of the chimney to which the pipe section 12 is attached will be directed through the pipe section 11 to the adjoining chimney. A damper 13 is provided in the pipe section 12 and as a hinge therefor I prefer to provide a rod 14 mounted in the wall of the pipe 12 at its intersection with the chimney and having a loop portion 15 to which the damper 13 or valve is connected. A crank 16 is mounted on the shaft 14 and has an operating handle 17 and is adapted to move over a rack 18 having notches therein for engaging the crank 16 and holding the damper in any of its adjusted positions. For instance, referring to Fig. 2, the full line position shows the passage to the flue entirely cut off, while in dotted lines I have shown the passage through the chimney partially and entirely closed. When this passage is entirely closed, as indicated by the horizontal dotted lines in Fig. 2, all the heat from the burner beneath will be directed through the flue sections 11 and 12 into the chimney adjoining and combined with the heat of the burner in this chimney, will very rapidly cook the contents of the utensil above. These flue sections may be made of any suitable gage of sheet metal and may be enameled, if preferred, to correspond to the finished surface of the metal chimneys.

In addition to doubling the amount of heat for cooking purposes, I have found that water in a wash boiler can be heated with a considerable saving in time. Stoves of this type are of such construction that a wash boiler when placed on the top of the stove will cover two of the adjoining chimneys. With my attachment the third chim-

ney will be included and the heat of three burners combined will greatly hasten the boiling of the water in the boiler.

It will be understood that this invention 5 may be applied to a stove having any number, more than one, of these burners and chimneys and connections may be made so that the heat of three of the burners will be combined in one chimney, if desired, and in 10 various ways the use of the attachment may be multiplied and still be within the scope of my invention.

I prefer to provide a removable ring 19 adapted to fit the top of a chimney for use 15 when the chimney is connected with one burner only. When, however, a chimney is coupled up with an adjoining one so that the heat of the two chimneys is combined in one, I may remove this ring to provide a 20 larger orifice in the top of the chimney.

In Fig. 2 I have shown the ring in place on one of the chimneys and removed from the other chimney.

I claim as my invention:

25 1. The combination, with a stove having burners and a chimney extending upwardly from each, of a flue connecting one chimney with an adjacent chimney above the burners thereof for conducting the heat from one 30 burner into the chimney of the adjacent burner.

2. The combination, with a stove and its burners and chimneys therefor projecting above the burners, of a flue mounted at an

incline to connect adjacent chimneys above 35 the burners, the upper end of the flue being adjacent to the upper end of the chimney with which it is connected, and a damper mounted to intercept the heat passing upwardly in one chimney and deflecting it 40 through said flue to the chimney of the adjacent burner.

3. The combination, with a stove, burners and the chimneys thereof, of a flue mounted to connect one chimney with another above 45 the burner and having means for simultaneously closing one chimney and directing the heat of the burner in said one chimney through said flue into the other chimney to supplement the heat from the burner of the 50 latter chimney.

4. The combination, with an oil burning cook stove having burners and chimneys extending a considerable distance above the burners and a stove top above the chimneys 55 having openings therein for the cooking utensils, of a flue between the burners and the stove top and leading from one chimney to another, and a single damper mounted to close the passage in a chimney between its 60 burner and the stove top and open the passage through the flue to the adjacent chimney, or close said flue and open the passage through the chimney.

In witness whereof I have hereunto set my 65 hand this 11th day of March, 1920.

FRANCIS J. PRIDEAUX.
